8 Claims. (Cl. 317—130)

This invention relates to electrical timers for establishing a preselected time delay between the occurrence of two events.

In general, the principles of the present invention are applied to a timer for use as an element of a system for dispensing a controlled quantity of liquid into each of a succession of containers. The containers are transported on a continuously moving conveyor system past a liquid dispensing nozzle. When a preselected relationship exists between a container and the nozzle, as determined by a photoelectric sensing arrangement, a solenoid is actuated to cause the liquid to be discharged into the container. With a constant flow rate, timing of the period of energization of the valve-controlling solenoid permits accurate control of the quantity of liquid which is delivered.

The present invention relates to improved photoelectric sensing, control and timing circuitry adapted for use in such a system, and through its practice improved accuracy and consistency of operation can be achieved with a minimization of maintenance cost and circuit malfunctioning.

The principles, objects and features of the invention will be understood from the following detailed description of a preferred embodiment thereof when read with reference to the drawing in which the single FIGURE illustrates in diagrammatic form a timing apparatus embodying the principles of the invention.

The system shown in the drawings is energized from an alternating voltage source 10 which, upon the closure of switch 12, is connected across the primary winding of transformer 14. The resultant alternating voltage induced in the center tapped secondary winding of transformer 14 is full-wave rectified by means of dual diode 16, is filtered by the capacitor-input resistance-capacitance filter network including capacitors 18 and 20 and resistors 22 and 24 and is applied across a pair of serially interconnected gaseous discharge voltage regulating devices 26 and 28. The anode of device 26 is grounded, a regulated negative voltage appears at the cathode of device 26 and hence at conductor 30 and a more negative voltage appears at the cathode of device 28 and hence at conductor 32.

The negative voltage between conductor 32 and ground is developed across serially interconnected resistors 34 and 36 which constitute a voltage divider network, with the value of resistor 34 being less than that of resistor 36 so that the voltage at conductor 38, interconnecting resistors 34 and 36, is appreciably negative relative to the voltage on conductor 30.

A photoelectric tube 40 is physically disposed in a position in the path of a light beam so that it is energized, and hence in a low-impedance state, at all times except when the light beam impinging upon that phototube is interrupted as by a can or other container traveling on the conveyor and passing, during its course of travel, through the light beam. The cathode of phototube 40 is connected to conductor 38 and the anode is connected to conductor 30 via conductor 44 and resistor 42. When the light beam impinges upon the phototube 40 so that its impedance is low, the potential at conductor 44 is quite negative relative to the potential at conductor 30 and approaches the potential at conductor 38. When that light beam is interrupted, phototube 40 assumes a high-impedance condition, that is, its resistance is high relative

2

to that of resistor 42, little current flows through resistor 42 and the potential at conductor 44 is but slightly negative relative to the potential on conductor 30.

A serially interconnected capacitor 46 and resistor 48 are connected in parallel with resistor 42, and resistor 48 is connected between the control grid and cathode of an electron discharge device 50, which illustratively takes the form of a pentode vacuum tube. Screen grid bias for tube 50 is derived through a potentiometer 52 the resistive element of which is connected between conductor 30 and ground. The suppressor grid is connected to the cathode, and the anode is connected to ground through the winding of a plate relay 54 having a pair of normally closed contacts 56. Relay 54 has two stable states, energized and released, and contacts 56 have two stable states, open and closed, respectively.

With light having impinged upon phototube 40 for a period of time and equilibrium conditions having been reached, the potential at the right-hand electrode of capacitor 46 will be substantially equal to the potential on conductor 38 so that there is substantially zero bias on tube 50, and the left-hand electrode of capacitor 46 will be at a potential approaching the potential of conductor 38 so that capacitor 46 will be charged with its left-hand electrode negative with respect to its right-hand electrode. Tube 50 will, under zero bias conditions, conduct sufficient anode current to energize plate relay 54 so as to open the contacts 56, as shown. When the light beam is interrupted as by a traveling object, phototube 40 is converted to a high-impedance condition, and conductor 44 tends instantaneously to change in potential toward the potential of conductor 30. Since the charge on capacitor 46 cannot change instantaneously, the right-hand electrode of capacitor 46 tends to be driven in a positive direction instantaneously, making the control grid of tube 50 positive relative to the cathode thereof. Since tube 50 is already conducting sufficiently to fully energize plate relay 54, this change will not effect the state of relay 54.

During the time that the light directed towards phototube 50 is interrupted, capacitor 46 will tend to discharge through resistors 42 and 48. With the parameters used in the constructed embodiment of the invention, the time constant of this circuit was but a few milliseconds and consequently in normal practice, capacitor 46 would tend to become substantially fully discharged during this interval and tube 50 would be returned substantially to a zero-bias condition.

When the impingement of the light beam upon phototube 40 is reestablished, the potential on conductor 44 tends instantaneously to approach the potential on conductor 38 and, since capacitor 46 cannot change charge instantaneously, the right-hand electrode thereof and the control grid of tube 50 are instantaneously driven in a negative direction, establishing a substantial negative bias on tube 50 and driving that tube towards or to grid cutoff or at least to the point at which the anode current is insufficient to maintain relay 54 operated. As a result, contacts 56 close. Capacitor 46 will then commence to charge through resistor 48 so that the potential at the control grid of tube 50 will gradually become less negative relative to the cathode and, after a preselected short interval, the anode current of tube 50 will increase to the point where plate relay 54 will again operate to again open contacts 56. In the preferred practice, the closed period of contacts 56 is but a few milliseconds in duration.

When contacts 56 are closed, a circuit is completed from ground, through the closed contacts, charging resistor 58, conductor 60, capacitor 62, and to the negative voltage on conductor 30. As a result, capacitor 62 is charged with its upper electrode positive relative to its lower electrode. Conductor 60, connected to the upper

electrode of capacitor 62, will change in potential during this charging period from a substantial negative value towards ground potential. In a constructed and preferred embodiment of the invention, the time constant of the circuit including resistor 58 and capacitor 62 was greater than the sum of the time constant of the RC circuit at the input of tube 50 plus the release and operate times of relay 54 so that the extent of the charge on capacitor 62 was determined primarily by the closed time of contacts 56. While conductor 60 does not reach ground potential during this period, it sufficiently closely approaches ground to bias tubes 64 and 66 quite substantially conductive.

Tubes 64 and 66 are illustrated as dual triodes with all four sections connected in parallel, with the control grids connected to conductor 60, with the cathodes connected to ground, and with the anodes being connected through the winding of solenoid 68 to a source of direct voltage comprising a half-wave rectifier 70 supplied from source 10 and a filter network comprising capacitors 72 and 74 and resistors 76, the anode to cathode voltage for tubes 64 and 66 being developed across capacitor 74.

When tubes 64 and 66 are rendered conductive, solenoid 68 is actuated. This may be considered to be the load device for the system. Solenoid 68 can be employed to actuate a valve to cause liquid to be ejected from a nozzle, but in the preferred practice, solenoid 68 physically deflects a nozzle through which liquid is continuously flowing from a position in which the liquid is directed over a return path to a position in which the liquid is directed into the container. The delay between the reestablishment of the light beam and the instant of actuation of the solenoid may be adjustable if desired.

When contacts 56 open, the above described charging circuit for capacitor 62 is disestablished and that capacitor commences to discharge through a series network, including fixed resistor 78, variable resistor 80 and calibrating resistor 82, connected in shunt of capacitor 62. As a result of this discharge, the potential on conductor 60 and hence at the control grids of tubes 64 and 66 will gradually become more negative. After capacitor 62 is discharged to a preselected degree, the potential on conductor 60 will have become sufficiently negative to reduce the current in tubes 64 and 66 to the point where solenoid 68 will release, to close the liquid dispensing controlling valve or to shift the nozzle so that the stream is directed over a return path.

The time constant of the circuit including capacitor 62 and resistors 78, 80 and 82 is preferably substantially longer than the time constants of the circuit hereinbefore described so that the liquid may be ejected from the nozzle for an appreciable period. In the above noted constructed embodiment, time delays from a few milliseconds to a substantial period were provided.

It will be observed that the circuit is operated on a direct current basis and that the contacts 56 are only called upon to carry the small amplitude charging currents for capacitor 62 rather than the relatively large amplitude (approaching an ampere) for energizing the solenoid 68.

The arrangement as above described produces actuation of the solenoid 68 in response to the reestablishment of the light beam following an interruption thereof, that is, the action is initiated or triggered in response to movement of the trailing edge of the container past a pre-selected point. It is also contemplated that the action may be triggered in response to the leading edge of the container, that is, in response to the interruption of the beam following a period of establishment of the beam. This can be accomplished, in one manner, by reversing the connections to the two electrodes of phototube 40 and correspondingly adjusting the direct voltages applied to those electrodes. For example, in the illustrated arrangement, correct operating potentials are applied to the electrodes of tube 40 by connecting the anode thereof

through resistor 42 to conductor 30, the potential of which is negative with respect to ground by the magnitude of the voltage across regulator 26, and by connecting the cathode to conductor 38. If resistors 34 and 36 were equal (assuming tubes 26 and 28 to be identical) the potential at conductor 38 would equal that at conductor 30. Consequently, as above noted, resistor 34 is selected to have a smaller value of resistance than resistor 36, with those values being selected to apply a potential to the cathode of tube 40 which is negative relative to the potential at conductor 30 by a preselected amount. To modify the equipment to respond to the leading edge of the container, resistors 34 and 36 can be interchanged and the connections to the anode and cathode of tube 40 reversed. In a constructed embodiment, resistors 34 and 36 had values of 33,000 ohms and 100,000 ohms, respectively. For the changed mode of operation, resistors 34 and 36 would have representative values of 100,000 ohms and 33,000 ohms, respectively, the anode of tube 40 would be connected to the junction of resistors 34 and 36, and the cathode of tube 40 would be connected to conductor 44. No other circuit changes are necessary.

While it will be apparent that the embodiments of the invention herein disclosed are well calculated to fulfill the objects of the invention, it will be appreciated that the invention is susceptible to modification, variation and change without departing from the proper scope or fair meaning of the subjoined claims.

What is claimed is:

1. In a control equipment effective in response to the transient change of a light beam by a movable object to actuate a load device for a selectable interval of time, the combination of relay means having two stable states, a photoelectric device in the path of the light beam, means including said photoelectric device and first timing means responsive to a change of the illumination on said photoelectric device in one direction for changing the state of said relay means from a first to a second state for a preselected short interval of time and effective thereafter even in the absence of a subsequent change of the illumination on said photoelectric device to change the state of said relay means from said second state to said first state at the end of said preselected short interval of time, a capacitor, a resistor, a source of energy, means including said relay means and said source and effective while said relay means is in said second state for changing the charge on said capacitor in one direction, means including said resistor effective while said relay means is in said first state for changing the charge on said capacitor in the opposite direction and at a rate controlled by said resistor, and means including amplifying means for operating the load device while the charge on said capacitor differs in one direction from a preselected magnitude and while said relay means remains in said first state and for releasing the load device when the charge on said capacitor differs in the other direction from said preselected magnitude.

2. In a control equipment effective in response to the transient change of a light beam by a moving object to actuate a load device for a selectable interval of time, the combination of first timing means for operating the load device for the selectable interval of time, an electron discharge device having conductive and nonconductive states, a pair of contacts, means including said electron discharge device for switching said contacts from one to another of two stable states in response to changes of the state of said electron discharge device, a photoelectric device in the path of said beam, and means including said photoelectric device and second timing means for biasing said electron discharge device to one of said states and effective in response to the transient change of the light beam for changing the state of said electron discharge device from a first to a second one of said states for a preselected short interval of time and effec-

tive thereafter even in the absence of a subsequent change in the illumination on said photoelectric device and independently of said first timing means to change the state of said electron discharge device back to said first state at the end of said preselected short interval of time, said preselected short interval of time being short relative to said selectable interval of time, said first timing means being controlled by said electron discharge device and comprising a capacitor, means effective while said contacts are in one of said states for changing the magnitude of the charge on said capacitor in one direction, means effective while said contacts are in the other one of said states for changing the magnitude of the charge on said capacitor in the other direction, and means effective only while the charge on said capacitor exceeds a preselected magnitude for operating the load device.

3. In a control equipment effective in response to the transient change of a light beam by a moving object to actuate a load device for a selectable interval of time, the combination of an electron discharge device having conductive and nonconductive states, a pair of contacts, means including said electron discharge device for switching said contacts from one to another of two stable states in response to changes of the state of said electron discharge device, a photoelectric device in the path of said beam, means including said photoelectric device and first timing means for biasing said electron discharge device to one of said states and effective in response to the restoration of the light beam following interruption of the light beam for changing the state of said electron discharge device for a preselected short interval of time the duration of which is independent of the duration of interruption of the light beam, a load device, and means including second timing means effective after and in response to a change of said first contact from said one to said other of said stable states followed by a change from said other to said one stable state for operating said load device for a different preselected interval of time.

4. In a control equipment effective in response to the transient interruption of a light beam by a moving object to actuate a load device for a selectable interval of time, the combination of an electron discharge device having conductive and nonconductive states, a pair of contacts, means including said electron discharge device for switching said contacts from one to another of two stable states in response to the changes of the state of said electron discharge device, a photoelectric device in the path of said beam, means including said photoelectric device and first timing means for biasing said electron discharge device to one of said states and effective in response to the restoration of the light beam following interruption of the light beam for changing the state of said electron discharge device from a first to a second one of said states for a preselected short interval of time the duration of which is independent of the duration of the interruption of the light beam and independent of the duration of the restored illumination from the light beam and second timing means controlled by said contacts for operating the load device for the selectable interval of time comprising a capacitor, a first resistor, a source of energy, means including said contacts and effective while said contacts are in said other state for effecting a charging circuit for said capacitor including said first resistor and said source, a second resistor, means including said second resistor connected in shunt of said capacitor effective while said contacts are in said one state for discharging said capacitor at a rate controlled by said second resistor,

another electron discharge device, and means including said other electron discharge device having the load device in the anode circuit thereof effective only while the charge on said capacitor exceeds a preselected magnitude for operating the load device.

5. In a control equipment effective in response to the transient interruption of a light beam by a moving object to actuate a load device for a selectable interval of time, the combination of an electron discharge device having conductive and nonconductive states, a pair of contacts, means including said electron discharge device for switching said contacts from one to another of two stable states in response to changes of the state of said electron discharge device, a photoelectric device in the path of said beam, means including said photoelectric device and first timing means for biasing said electron discharge device to one of said states and effective in response to the interruption of the light beam for changing the state of said electron discharge device for a preselected short interval of time the duration of which is independent of the duration of interruption of the light beam, a load device, and means including second timing means effective after and in response to a change of said contacts from said one to said other of said stable states followed by a change from said other to said one stable state for operating said load device for a different preselected interval of time.

6. The combination of claim 1 further including a second resistor connected in shunt of said capacitor and in which said amplifying means comprises another electron discharge device having the load device in the output circuit thereof.

7. In a control equipment effective in response to the transient change of a light beam by a movable object to actuate a load device for a selectable interval of time, the combination of relay means having two stable states, a photoelectric device in the path of the light beam, means including said photoelectric device and first timing means responsive to a change of the illumination on said photoelectric device in one direction for changing the state of said relay means from a first to a second state for a preselected short interval of time determined by said first timing means and effective thereafter even in the absence of a subsequent change of the illumination on said photoelectric device to change the state of said relay means from said second state back to said first state at the end of said preselected short interval of time, and second timing means controlled by said relay means and effective in response to the change of state of said relay means from said first state to said second state and back to said first state for operating the load device for a selectable length of time longer than said preselected short period of time.

8. The combination of claim 7 in which each of said first and said second timing means includes a resistor and a capacitor connected in a change-of-charge circuit with said resistor.
